UNITED STATES PATENT OFFICE.

AUGUST W. MELANDER, OF SAN FRANCISCO, CALIFORNIA, ASSIGNOR TO SWAN J. STERNER, OF SAN FRANCISCO, CALIFORNIA.

DOOR-STOP.

1,111,485.

Specification of Letters Patent. Patented Sept. 22, 1914.

Application filed June 3, 1912. Serial No. 701,191.

To all whom it may concern:

Be it known that I, AUGUST W. MELANDER, a subject of the King of Sweden, residing in the city and county of San Francisco and State of California, have invented 5 certain new and useful Improvements in Door-Stops, of which the following is a specification.

The hereinafter described invention relates to new and useful improvements in door stops and particularly to a type of door stop which will limit the opening of the door, when desired, so that undesirables cannot force an entrance, upon the door being 15 open to admit of their inspection.

The invention has for its principal object to provide a door stop of such construction that when the same is in operative relation the door cannot be opened to a greater distance than the limit of the stop except by 20 first completely closing the door and then throwing the stop into inoperative relation.

Another object is to provide a door stop having an enlarged end adapted to enter a 25 groove in a floor plate and to provide said stop with an eccentrically mounted operating means extending within easy reach of the operator and by the operating of which the enlarged end of the stop may be readily 30 inserted into or withdrawn from the floor plate when the door is in proper position.

The invention consists of a door bolt or plunger attached on the inner side of a door adjacent the lower edge thereof and having 35 an enlarged lower end, a casing in which said bolt is mounted to reciprocate, an operating means for said bolt, and an open ended slotted plate adapted to be secured to the floor adjacent the door and into which 40 said enlarged head is adapted to be inserted and slide, the slot in said plate limiting the movement of the door when the enlarged head is inserted therein.

With the above mentioned and other objects in view the invention consists in the novel construction and combination of parts, hereinafter fully described, illustrated in the accompanying drawings, and pointed out in the claims hereto appended.

50 Referring to the drawings disclosing a completely constructed device for carrying out my invention,—Figure 1 is a front elevation of the inside of a door having my improved device attached thereto and in co-operative relation with the slotted floor plate,

and disclosing in full lines the enlarged bolt head withdrawn from the floor plate, and in dotted lines the position of the several parts when the enlarged head is seated in said plate. Fig. 2 is an enlarged transverse 60 sectional view of Fig. 1, disclosing the construction of the casing in which the bolt is mounted, the bolt being inserted in the slot in the floor plate. Fig. 3 is a plan view of the floor plate disclosing the arcuate slot 65 therein and the enlarged opening at one end thereof for the reception of the enlarged head of the securing bolt when the door is in its closed position. Fig. 4 is an enlarged 70 sectional view of the securing bolt and the casing and spring surrounding the same.

Referring more particularly to the drawings, the reference numeral 1 designates a suitable door, hinged as at 2 to swing on the door casing as at 3 and having attached 75 to the inner side thereof adjacent its bottom edge and arranged near the free edge thereof, an oblong metallic casing 4 open at its lower end and provided with a small opening 5 at its upper end through which extends 80 the upper cylindrical portion 6 of a substantially rectangular plunger 7. The casing 4 is provided with laterally extending flanges 8 through which extend suitable screws 9 which attach the casing to the door 85 as in Fig. 1 of the drawings.

Surrounding the cylindrical portion 6 of the plunger 7 with its lower edge resting on the shoulder 10 and its upper edge contacting with the inner face of the upper end of 90 the casing 4, is a coiled compression spring 11 adapted to force the plunger downwardly for a hereinafter described purpose.

Pivotedly connected through an eye 12 in the upper end of the cylindrical portion 6 of the plunger 7 is the lower end of an operating rod 13, the upper end of which is pivotally mounted to a stud 14 projecting outwardly from an operating lever 15 midway of its length. The lever 15 is pivoted at its lower end to a stud 16 projecting from the lower edge of a securing plate 17 attached to the door directly above the casing 4, and the plate is provided at its upper edge with an outstanding lug or projection 18 arranged at an angle to the center of said plate. An operating handle 19 is provided at the upper end of said lever 15, the lever and rod providing an eccentrically mounted operating means for the plunger.

A metallic plate 20 is secured over an opening in the floor 21 immediately below the plunger 7 and said plate is provided with a longitudinally extending curved slot 22, closed at its rear end, and at its front end communicating with an enlarged opening 23, through which is adapted to extend suitable laterally projecting arms 24 arranged one on either side of the plunger 7 adjacent its lower end. The plate when in position is arranged with the enlarged opening 23 immediately below the plunger when the door is in a closed position, and with the curved slot projecting in the direction of the swing of the door.

From the above description it will be observed that when the operating lever 15 is in a position abutting against the projection 18, the plunger will be withdrawn from the opening 23 of the plate 20, but the plunger can only be withdrawn from the opening when the door is in a closed position. It will also be observed that when the door is closed and the lever 15 is swung to the point A, that the spring 11 will force the arms 24 downwardly into the opening 23 and that the door can only be opened to the limit of the slot 22, the edges of the slot preventing the withdrawal of the arms 24.

By the employment of my improved construction it will be noted that it is impossible for an undesirable to force the door from without as the plunger cannot be removed from the plate until the door is in a closed position, and it will also be noted that should an undesirable partly open the door and surreptitiously remove every screw from the device permitting the door to swing

freely, that the plunger would continue to limit the opening of the door and the same could not be removed from the plate until the door is closed, and when the door is in a closed position it is impossible for a person from without to operate.

Having thus fully described my invention what is claimed as new and desired to be protected by Letters Patent is—

In a door stop, the combination with a casing mounted on the interior of the door, a plunger mounted to reciprocate in said casing, arms projecting laterally from the lower end of said plunger, means associated with the upper end of said plunger for operating the same, a stationary floor plate mounted adjacent the door when in a closed position for coöperation with said plunger and provided at one end at a point below the plunger when the door is in a closed position with an enlarged opening through which the lower end of said plunger and said arms are adapted to be projected when the door is in a closed position, and a contracted slot closed at one end and curved in the arc of the swing of the door and communicating at its opposite end with said enlarged opening and adapted to receive the plunger and limit the opening of the door when said plunger is inserted therein.

In testimony whereof I have signed my name to this specification in the presence of two subscribing witnesses.

AUGUST W. MELANDER.
